UNITED STATES PATENT OFFICE.

RALPH W. H. ATCHERSON, OF INDIANA HARBOR, INDIANA.

ART OF REMOVING FLUE DUST FROM CONTAINERS.

Application filed September 12, 1921. Serial No. 500,149.

To all whom it may concern:

Be it known that I, RALPH W. H. ATCHERSON, a citizen of the United States, residing at Indiana Harbor, in the county of Lake and State of Indiana, have invented a new and useful Improvement in the Art of Removing Flue Dust from Containers, of which the following is a specification.

My invention relates, more particularly, 10 to the conveying, or carrying away, of dust from any structure containing dry flue dust discharged from blast furnaces, as for example dust catchers, dust pockets, dust-receiving spaces in cleaners of the filter-pad 15 type, electrical precipitators and tangential whirlers.

The removal of the dust economically and 20 without danger to the workmen or equipment, from structures in which it is disposed, either for discharge as waste, for treatment and return to the blast furnaces, or for other disposal, has presented a great problem in the practical operation of blast furnace systems.

25 The common practice has been to load the flue dust into cars, but such handling of the dust has presented many objections certain of which are the danger of injury to the workmen and equipment, not only from escaping gas, but also from the dust, especially when the dust is hot, the great attendant expense, which includes the cost of cars for such use, the cost of operating the same comprising the cost of motive power for 30 the cars and the labor for operating them which latter is augmented when the cars are overloaded with the dust and replacement in the cars of the dust spilled therefrom, is required, the irregularity of the operation 35 of the blast furnace gas-cleaning system during the emptying of the dust-catcher, or other dust container, and the impairment of the efficiency of the dust-catchers, or other dust containers, due to the containers becoming 40 partially filled with dust and becoming beclouded.

The purpose of my invention, generally stated, is to provide for the handling of the flue-dust in a manner preferably not to interfere with the continued operation of the furnace and the apparatus associated therewith including the dust catcher, or other container, in which the dust is caused to become disposed, and in a manner to avoid injury to the workmen and equipment, conserve the gas generated by the blast-furnace,

and to minimize the expense of such disposal, both from the standpoint of original cost of the apparatus and its upkeep, and the labor cost for operation; and generally 60 to improve upon prior practices of flue-dust disposal or transfer.

Referring to the accompanying drawing: Figure 1 is a view in elevation of an installation embodying my invention and involving, as a part of a blast furnace equipment, a dust-catcher and a gas-washer, and means for transferring, or conveying, the flue-dust precipitated in the dust-catcher, all in accordance with my invention; and Figure 2, a similar view, with certain portions of the apparatus shown in Fig. 1 broken away, showing another arrangement of the parts illustrated in Fig. 1 and embodying my invention.

I have chosen to illustrate my invention in connection with apparatus designed to receive the flue-dust directly from a blast furnace and effect its separation from the products of combustion with which it is mixed, but it will be understood that the invention is not limited to employment in such an apparatus.

In the particular arrangement shown in Fig. 1, 3 represents a conduit which leads from the outlet of a blast-furnace (not shown) this conduit or down-comer opening at its lower end into a dust-catcher represented at 4 which may be of any desirable construction, such, for example, as is commonly in use and wherein the "dust" entering it with the products of combustion from the blast furnace, is caused to become precipitated into the lower hopper-shaped end of the catcher 4, the hopper-formed portion of the catcher in the particular construction shown constituting the bottom wall of the body portion of the container. The catcher is shown as provided at its top with a conduit 6 which opens at one end into the catcher and at its opposite end into a gas-washer 7, as shown into the bottom of the latter, which may be of any desirable construction such, as for example, as is now commonly in use wherein the products of combustion discharging from the catcher 4 are permitted to rise in the washer in opposition to, and in contact with, a descending spray of water introduced into the washer, in a manner not shown, preferably adjacent its upper end, and in which operation the finer suspended solid matter carried over

with the gases into the washer, are thrown down with the water and discharged with the latter through an outlet pipe 8, the washer being provided with a gas outlet pipe 9 through which the gases are conveyed to any desired point in accordance with common practice.

The lower end of the catcher 4 is shown as formed with a spout portion 10 into which 10 the upper end of a pipe 11 shown as inclining downwardly, and preferably valved at 12, opens, the lower end of this pipe opening into a substantially vertical pipe 13, the lower open end of which is provided with a 15 valve 14, the pipe 13 opening above the valve 14 and below the point of connection of the pipe 11 with the pipe 13, into a pipe 15 preferably formed with an upwardly-extending bend 16, the outer end of the pipe 15 being 20 located directly above a sluicing gutter, flume, or sewer 17. The pipe 13 communicates with one end of a pipe 18 above the point at which the pipe 11 opens into it, the other end of pipe 18 opening into the pipe 25 25 8 through a coupling 19, the lower branch 20 of which is valved, its side branch 21 opening into a pipe 22 formed with an upwardly-extending bend 23 extending at a 30 higher elevation than the highest point at 30 which the piping leading from the other side-branch 24 of the coupling 19, extends, the extremity of the pipe 22 being open and extending above the gutter 17 whereby, should the piping leading away from the side 35 branch 24 become clogged, the washing water may escape from the washer through the pipe 22.

In the operation of the apparatus the 40 flue-dust precipitated in the catcher 4 descends in dry condition through the pipe 11 and into the pipe 13 wherein it is contacted by the wash water flowing from the washer 7 through the pipes 8, 18 and 13. The water flowing through the pipe 13 commingles 45 with the "dust" supplied to the pipe 13 as stated, and the intermixed water and "dust" discharges from the pipe 13 into the pipe 15 and thence into the trough 17 through which latter it flows to any desired point for settling of the dust from the water and subsequent use or treatment, or the disposal thereof of otherwise.

The catcher 4 is shown as provided with an outlet 25 at its lower end controlled by 55 a valve 26 which permits of the discharge of the "dust" into a receptacle, as for example a car shown at 27 in case, for any reason, as for example should repairs be required on the piping referred to, it becomes desirable to 60 so dispose of the "dust."

The arrangement shown in Fig. 2 is the same as that shown in Fig. 1 except that the pipe 11 opens into pipe 13 above, instead of below, the point at which the pipe 18 65 opens into pipe 13, the "dust" descending in

the pipe 11 dropping into the water discharging from the pipe 18 into pipe 13.

In both arrangements shown it is preferred that the piping referred to be so proportioned and disposed that the flow of 70 water from pipe 18 into pipe 13 will not cause backing up of the water in the pipe 11.

The advantages of disposing of flue-dust in accordance with the foregoing will be 75 manifest. In the normal operation of the apparatus impregnating of the "dust" in pipe 11 with moisture sufficiently far back from the point of communication with the pipe 13 as to cause the "dust" to become 80 non-flowing to the pipe 13, is avoided. Provision is, however, made in the apparatus shown for the ready removal of any dust which may become dampened sufficiently to clog the pipe 11, by the provision of an 85 opening in the side of the spout-portion 10, said opening being normally closed by a plug, through which a suitable rod may be introduced into pipe 11, to force wet dust-accumulations therefrom and into pipe 13. 90

Under certain conditions it is desirable, for purpose of economy, to employ as the sluicing water for the "dust", the water discharged from the gas washer, but it will be understood that any other source of desirable fluid may be utilized regardless of its having been previously used for another purpose. It will also be understood that my improved method and apparatus may be utilized in connection with other arrangements than those involving a so-called "dust" catcher. These, as well as various other modifications, both as to the manner of practicing my improved method and as to the apparatus shown, may be employed 100 without departing from the spirit of my invention. 95

What I claim as new, and desire to secure by Letters Patent, is:

1. Apparatus for the purpose set forth, 110 comprising, in combination, a dust-container, a source of liquid, and piping connected with the discharge end of said container and with said source of liquid comprising a pipe section extending at an angle to the horizontal and containing an opening in its side wall, and other pipe sections leading from said liquid supply and from said discharge end, respectively, one of said last-referred-to pipe sections opening into the upper end of 115 said first-referred-to pipe section and the other thereof communicating with, and terminating at, said opening in the side wall of said first-referred-to pipe section. 120

2. Apparatus for the purpose set forth, 125 comprising, in combination, a dust-container, a gas washer, and piping connected with the discharge end of said container and with the liquid-outlet of said washer and comprising a pipe section extending at an angle to 130

the horizontal and in communication with the discharge end of said container, and a water-seal-forming pipe having an upwardly extending portion and leading from said 5 outlet of said washer to said first-referred-to pipe section for the purpose set forth.

3. Apparatus for the purpose set forth, comprising, in combination, a dust-container, a gas washer, piping connected with the 10 discharge end of said container and with the liquid-outlet of said washer and comprising

a pipe section extending at an angle to the horizontal and in communication with the discharge end of said container, and a pipe leading from said outlet of said washer in 15 an upward direction and communicating with said first-referred-to pipe section for the purpose set forth, and another pipe communicating with the liquid-outlet of said washer and extending to a higher elevation than said second-referred-to pipe. 20

RALPH W. H. ATCHERSON.
